UNITED STATES PATENT OFFICE

GEORGE B. LOUDERBACK, OF COMPTON, CALIFORNIA

DRILLING BIT

Application filed May 28, 1928. Serial No. 281,267.

In this specification, and the accompanying drawings, I shall describe and show a preferred form of my invention, and specifically mention certain of its more important objects. 5 I do not limit myself to the forms disclosed, since various changes and adaptations may be made therein without departing from the essence of my invention as hereinafter claimed; and objects and advantages, other than those specifically mentioned, are included within its scope.

My invention relates to drilling bits, and especially to bits used in rotary earth drilling. Its principal objects include: first, to provide an improved tool of this nature that embodies movable cutting blades that may be advanced from time to time as they become worn, to maintain the gauge of the drill hole; second, to supply hydraulic pressure means for advancing the blades while the tool is at the bottom of a drill hole, by alternately raising and lowering it; and, third, to accomplish the above purposes in a relatively simple and rugged construction 25 that may be depended upon to function as intended.

My objects are attained in the manner indicated in the accompanying drawings, in which—

30 Figure 1 is an elevation of the tool with the front half of the lower housing removed, to show the disposition of certain members of the operating mechanism in cooperative relation to the cutting blades;

35 Figure 2 is a central longitudinal section of the tool, taken on the line 2—2 of Figure 1;

Figure 3 is an enlarged elevation of the lower portion of the complete lower portion of the tool, in position for drilling at the 40 bottom of a drill hole;

45 Figure 4 is a further enlarged central longitudinal section of the intermediate portion of Figure 2, for the purpose of more clearly showing and explaining details of the operating mechanism;

Figure 5 is a cross section of the tool taken on the line 5—5 of Figure 4;

50 Figure 6 is a cross section taken on the line 6—6 of Figure 4;

Figure 7 is a cross section taken on the line 7—7 of Figure 4; and

Figure 8 is a cross section taken on the line 8—8 of Figure 1.

Similar reference numerals refer to similar parts throughout the several views.

In the following United States patents, viz.: #1,522,891, Jan. 13, 1925; #1,522,892, Jan. 13, 1925; #1,570,754, Jan. 26, 1926; and #1,615,547, Jan 25, 1927; I disclosed and described cutting blades for drilling bits, similar in type and general arrangement to those shown and described herein; and means for advancing them from the lower end of the tool, obliquely to its axis. The present invention differs from those mentioned in its blade-feeding mechanism, and only the latter is claimed herein.

The blade-feeding mechanism, constituting the present invention, is well adapted for use in a variety of tools of the general character mentioned above, and also in other devices requiring periodic feeding of the cutting blades.

The embodiment of this invention that I have selected for illustration, is a bit adapted for the rotary drilling of deep wells. The lower housing or body portion comprises two identically shaped halves 11 and 12, having accurately machined or ground faces, assembled face to face so as to contact closely and form a tight joint. These body halves are held together at their lower ends by means of through-bolts 13. Their upper ends are threaded at 14, and are screwed into the lower end of the upper tubular housing 15. The latter is provided at its top with a screw "pin" 16, whereby the tool is connected to a tool string for operative rotation, and there is an axial bore 17 through the pin for circulating purposes.

The lower body halves are so formed that, when assembled, the lower portion of the tool is somewhat in the shape of a wedge of elliptical section, as indicated in Figures 2 and 8. Their abutting faces are recessed, as at 18 and 19, to form enclosing chambers for members of the working mechanism; and channels 20 are provided in these faces for

obliquely guiding and positioning the cutting blades.

The tool is provided with a pair of oblique bifurcated cutting blades 21 and 22 which are transversely grooved at their upper ends to form flanges 23, for engaging a similarly grooved blade head 24, to be longitudinally positioned thereby. They are also provided with longitudinal flanges 25 on their leading faces. The blade head moves up and down in the shallow rectangular recesses 18. The longitudinal flanges of the blades engage the respective channels 20, and are constrained thereby to move obliquely. As blade head 24 is moved downward, the blades are fed obliquely from the end of the tool; their upper ends meanwhile traversing the blade head in engagement with its cross groove.

The feeding mechanism which is the subject matter of the present invention, comprises a piston rod 26, extending from blade head 24 and carrying a piston 27 at the top. It is the hydraulic pressure exerted against this piston from above that causes the blades to be advanced, and which resists their upward thrust. The piston works within a cylinder 28, having an inward flow one-way valve 29, in its upper head 30; and an angularly spaced arrangement of outward flow one-way valves 31, of substantially equivalent area, is provided in its lower head 32. A tubular shell 33, spaced from both cylinder 28 and housing 15, encloses the cylinder and its inlet valve.

Cylinder 28 and shell 33 respectively are screwed into and upon a tubular member 34, and the latter is screwed upon a central boss formed at the upper ends of the united body halves 11 and 12. Within the bore of member 34, below the head of cylinder 28 and slightly spaced therefrom, is a pump block 35. In cooperation with the adjacent parts, this block forms the closure of a chamber 36 beneath it. The pump block is provided with three angularly spaced one-way pressure pumps, the cylindrical bores of which are shown at 37. The piston rods 38 of these pumps extend downwardly through the block into chamber 36, and therein are surrounded by helical compression springs 39 for normally maintaining the pump plungers 40 at the bottom of their strokes.

The above described feed mechanism is actuated by means of a pair of longitudinal plunger rods 41, normally projecting from the lower end of the tool, and terminating in a shoe 42 at the bottom. These rods extend into chamber 36 and are united therein by a ring 43, which is of sufficient diameter to also engage the lower ends of pump rods 41. The plunger rods are free to slide up and down in recesses 19, and a strong helical compression spring 44, surrounding rod 26, tends to keep the rods pressed down as shown in Figure 2.

Packing boxes 45 and 46 pack rod 26 where it passes through cylinder head 32 and pump block 35 respectively.

Cylinder 28, space 48 beneath it, and space 49 surrounding it, are filled with a light oil or other suitable fluid; and a series of angularly spaced small passages 50 connect spaces 48 and 49. When pump plungers 40 are pushed upwardly, oil is forced thereby through passage 50, space 49, and valve 29 into cylinder 28 above piston 27. The hydraulic pressure forces the piston downwardly to advance the cutting blades of the tool. Oil beneath piston 27 is forced out from the cylinder, through valves 31.

When the tool is in operation, the cutting blades are advanced to the position shown in Figure 3. At that time the weight of the tool and tool string is largely, if not entirely, upon the cutting blades; and plunger rods 41 are pushed part way into the tool for the reason that shoe 42 rests upon the bottom of drill hole 47. After the blades have become worn, and it is desired to advance them further, the tool first is raised to allow the plunger rods to become fully extended, and then is lowered to push the rods in again. This operation works pump plungers 40, and puts a hydraulic pressure upon piston 27, in the manner explained above. By reason of the relatively very small diameter of the pump plungers, a heavy hydraulic pressure may be exerted in this way upon piston 27. For similar reasons the movement of piston 27 is only a small fraction of the stroke of the pump plungers. The operation just described may be repeated to cause any desired advancement of the blades.

Circulating water is fed to the blades through bore 17, space 51 between shell 33 and housing 15, and the small passages 52, leading from space 51 to the lower ends of body halves 11 and 12, and discharging in front of the respective cutting blades.

Having thus fully described the construction and operation of my invention, I claim:

1. A drilling bit comprising; a body; cutting blades adapted for being advanced from the body obliquely to its axis; a ram adapted for advancing said blades; longitudinally slideable plunger rods normally projecting from the end of said bit; and means whereby an hydraulic pressure may be exerted upon said ram by the longitudinal sliding of said rods.

2. A drilling bit comprising; a body; cutting blades adapted for being advanced from the body obliquely to its axis; an hydraulic ram adapted for advancing said blades; longitudinally slideable plunger rods normally projecting from the end of said bit; and pump means interposed said rods and the ram whereby an hydraulic pressure may be exerted upon the ram by the longitudinal sliding of the rods.

3. A drilling bit comprising; a body; cutting blades adapted for being advanced from the body obliquely to its axis; a cylinder within the body; a piston, slideable within said cylinder, having a piston rod connected to said blades for advancing them; a pump within the body whereby an hydraulic pressure may be exerted upon said piston; and plunger rods normally projecting from the end of said bit, adapted by longitudinal reciprocation to operate said pump.

4. A drilling bit comprising; a body; cutting blades adapted by longitudinal sliding to be advanced from the end of the body obliquely to its axis; a cylinder within the body; a piston, slideable within said cylinder, having a piston rod operatively connected to said blades for advancing them; a pump within the body, operatively connected to said cylinder, whereby an hydraulic pressure may be exerted upon said piston; plunger rods normally projecting from the end of said bit, adapted by longitudinal reciprocation to operate said pump; and a spring, opposing the longitudinal movement of said plunger rods and adapted to restore them to their normal position.

5. A drilling bit comprising; a body; movable cutting blades projecting from the body; longitudinally slideable plunger rods that normally project from the end of said body; and hydraulic pressure means for progressively advancing said blades; said means being adapted for actuation by reciprocating said rods.

6. A drilling bit comprising; a body; movable cutting blades projecting from the body, and adapted for being advanced obliquely to the axis thereof; longitudinally slideable plunger rods that normally project from the end of said body; and hydraulic pressure means for progressively advancing said blades; said means being adapted for actuation by reciprocating said rods.

45 GEORGE B. LOUDERBACK.
